UNITED STATES PATENT OFFICE.

DUDLEY H. WIGGINS, OF WASHINGTON TOWNSHIP, MARION COUNTY, INDIANA.

DESIGN FOR A GAME-BOARD.

47,370.

Specification for Design.

Patented May 18, 1915.

Application filed January 28, 1915. Serial No. 4,957. Term of patent 7 years.

To all whom it may concern:

Be it known that I, DUDLEY H. WIGGINS, a citizen of the United States of America, residing in Washington township, in the county of Marion and State of Indiana, have invented a new and original and ornamental Design for a Game-Board, of which the following is a specification, reference being had to the accompanying drawing, forming a part thereof.

The figure is an elevation of the game board.

I claim:

The ornamental design for a game board, as shown.

DUDLEY H. WIGGINS.

Witnesses:

J. H. WELLS,
M. TURBYVILLE.
